UNITED STATES PATENT OFFICE.

RICHARD F. HAYES, OF NEW YORK, N. Y.

BRACE FOR PACKING HATS.

SPECIFICATION forming part of Letters Patent No. 240,128, dated April 12, 1881.

Application filed February 15, 1881. (No model.)

To all whom it may concern:

Be it known that I, RICHARD F. HAYES, a citizen of the United States, residing at New York, in the county and State of New York, have invented new and useful Improvements 5 in Braces for Packing Hats, of which the following is a specification.

This invention has for its object to retain a hat, when the same is placed in a box, firmly 10 in position, so that in shipping the box the hat is not liable to sustain any injury by the jar of railroad-cars, or by careless handling of the packages during transportation.

My invention consists, essentially, in the combination, with a box for packing hats, of a 15 brace formed of a strip of metal or other material, having a depression to fit within the head-opening of the hat, and constructed at each end with an arm to bear on the brim of 20 the hat, the said arms being bent upwardly, and provided with means attaching them to the packing-box, all of which will be fully hereinafter described.

In the accompanying drawings, which illustrate my invention, Figure 1 represents a 25 plan or top view of a hat-box furnished with my brace. Fig. 2 is a central section of the same. Fig. 3 is an end view of the brace detached.

30 Similar letters indicate corresponding parts. In the drawings, the letter A designates my brace, which is, by preference, made of a strip of sheet metal, but which may also be made of a strip of pasteboard or other equivalent 35 material. Said brace is provided with a depression, a, formed to fit the head-opening of the hat, and with arms b, which extend in opposite directions, and are intended to bear upon the face of the brim of the hat to be 40 packed, as shown in Fig. 2. The outer ends of the arms b are bent upward, as shown in Figs. 2 and 3, and they are provided with 45 spurs c. (Best seen in Fig. 3.)

In manufacturing my braces I make them of 45 different sizes to, correspond to the different sizes of hats, so that for each hat to be packed a brace of corresponding size can readily be picked out.

50 In packing hats I use a box, B, of the usual form and construction. The boxes generally used for this purpose are made of pasteboard

and of suitable size to contain three or more hats, as shown in Fig. 2. To the bottom of each box is firmly secured a cylinder, d, for the reception of the crown of the largest hat 55 in the lot or nest, and between the inner surface of this crown and the crown of the next succeeding hat is placed a ring, e, of pasteboard or card-board, and so on to the last hat in the nest. If the cover C of the box is put 60 on, and the box is transported in vehicles or railroad-cars, the jar to which the box is necessarily exposed acts injuriously on the hats, and particularly the brim of the last or smallest hat in the nest is liable to become damaged by abrasion and being bent out of shape. This difficulty is prevented by my brace A, the depression a of which fits the head-opening of the last or smallest hat in the nest, while the arms b extend over and bear down upon the face of 70 the brim of said hat, and are secured in position by bending their ends down over the top edge of the box and fastening them thereto by means of the spurs c, as shown in Fig. 2.

If desired, the spurs c may be left off, and 75 the brace can be fastened simply by clamping the top edge of the box firmly between the ends of the arms b, or other suitable means for fastening the brace in position may be used.

It will be evident that by the employment 80 of a strip to form the brace, as hereinbefore described, it is capable of fitting and holding a hat of any ordinary size, because the strip can be bent or made to adapt itself to the size of the head-opening of the hat.

85 By the action of my brace the hat or hats contained in the box A are retained firmly in position, and they are not liable to become damaged by transportation, or by careless handling of the packages.

90 I am aware that a hat-box has been provided with a cover having a depressed body portion to enter the head-opening of the hat for the purpose of retaining the hat in place; but such does not constitute my invention.

95 What I claim as new, and desire to secure by Letters Patent, is—

1. The combination, with a box for packing hats, of the brace A, formed of a strip of metal or other material, having a depression, 100 a, to fit within the head-opening of the hat, and constructed with arms b b, arranged to

bear on the brim of the hat, and having their outer ends bent upwardly, and provided with means attaching them to the packing-box, substantially as shown and described.

5 2. The combination, with a box for packing hats, of the strip A, of metal or other material, formed with a depression, a, and arms b b, the ends of which are bent upwardly and clasp the upper edge of the box, and are pro-

vided with spurs entering the box, all substantially as and for the purpose described.

In testimony whereof I have hereunto set my hand and seal in the presence of two subscribing witnesses.
